Inventor:

Robert F. Bracke

Williams Bradley, Wm. C. S. & Co., Atty's.

UNITED STATES PATENT OFFICE.

ROBERT F. BRACKE, OF CHICAGO, ILLINOIS, ASSIGNOR, BY MESNE ASSIGNMENTS, TO CURTIS B. CAMP, TRUSTEE, OF OAK PARK, ILLINOIS.

MANIFOLD FOR INTERNAL-COMBUSTION ENGINES.

Application filed April 17, 1922. Serial No. 554,180.

To all whom it may concern:

Be it known that I, ROBERT F. BRACKE, a citizen of the United States, and resident of Chicago, in the county of Cook and State of Illinois, have invented a certain new and useful Improvement in Manifolds for Internal-Combustion Engines, of which the following is a full, clear, concise, and exact description, reference being had to the accompanying drawing, forming a part of this specification.

My invention relates to manifolds for internal combustion engines, and particularly to a single casting embodying both the intake and exhaust manifolds, and also an air passage for conducting the air to the carburetor.

A primary feature of my invention is the provision of a manifold in which the passage for heating the air before it passes through the carburetor and that leading from the mixing chamber of the carburetor to the intake ports of the engine are both brought to a single surface upon which the carburetor may be attached, whereby through a single flange both the intake and discharge passages to and from the carburetor may be connected with the corresponding passages of the manifold.

Another feature of the invention resides in the particular method of associating the air passage with the exhaust manifold so as to take advantage of radiation from the exhaust manifold in heating the air before it enters the carburetor.

My invention is illustrated in the accompanying drawing in which—

Figure 1 is an elevation of the manifold, partly in section, to which a carburetor is shown attached;

Figure 2 is a section on the line 2—2 of Figure 1;

Figure 3 is a section on the line 3—3 of Figure 2, with the carburetor omitted; and

Figure 4 is a section on the line 4—4 of Figure 1, illustrating the plan of the flange face.

In carrying out my invention, I preferably cast the manifold as a unit having an exhaust gas passage 5 communicating with the openings 6 for receiving its exhaust gases from the engine cylinder block through the usual form of flange 7. This exhaust passage discharges through an

opening at 8 into the exhaust pipe and 55 muffler, not shown.

The fresh air intake passage 9 extends throughout the length of the manifold near the top thereof, and returns to substantially the central part of the manifold where it turns outwardly at 10, terminating in the opening 11 in flange 12. This fresh air intake passage lies adjacent the exhaust passage throughout a large portion of its length, so that the air passing through it 60 is heated. A screw-threaded plug 13 is provided in the forward end of this passage, so that it may be removed in hot weather to prevent overheating the air.

The manifold intake passage extends upwardly from the opening 14 in the flange 12, and branches through passages 15 to the flanged openings 16, entrances to the engine block, not shown.

The carburetor 18 is provided with a U-shaped passage 19 in one limb of which a Venturi tube 20 is arranged about a nozzle 21. Ducts 22, 23 and 24 are provided for the maintenance of a proper mixture for idling the engine. This carburetor is also 70 provided with a choke throttle 25, and with the usual butterfly valve 26 for governing the flow of air to the engine.

By the use of my invention, the intake and discharge connections between a carburetor and an engine manifold are completed through the same act as is ordinarily performed in connecting the discharge opening of the carburetor with the manifold. At the same time, flexible tubing, such as is often used for conducting warm air to the carburetor, is eliminated.

While I have shown and described my invention with respect to certain details of construction, it is to be understood that many modifications are possible without departing from the spirit or scope of the invention, and I therefore do not wish to be unduly limited to the specific embodiment herein illustrated.

What I claim is:

1. A manifold for internal combustion engines comprising three distinct passageways, one for exhaust gases, one for carburetted air, and one for fresh air anterior to its carburetion, and a single flange to which the latter two passages lead for the connection of a carburetor thereto.

2. A manifold for internal combustion engines comprising an exhaust gas passage extending throughout the length of the manifold, a fresh air passage leading from one end of the manifold to the other and then back upon itself to substantially the central part of the manifold, a carburetted air passage, a flange within which the latter two passages terminate, and a carbureter having a similar flange through which air is received from one of said passages and delivered to the other.

3. A manifold for internal combustion engines comprising an exhaust gas passage extending throughout the entire length of the manifold, an intake manifold in heat conducting relation to said exhaust passage, a fresh air passage extending along the manifold from the discharge end of the exhaust

passage to the other end of the manifold 20 and then backwardly to the center of the manifold, and a connection forming a part of said manifold for conducting the air from said fresh air passage to a carbureter.

4. A manifold for internal combustion engines comprising an exhaust gas passage extending throughout the length of the manifold, a fresh air passage extending from one end of the manifold to the other and then back to substantially the middle of the manifold, and a removable plug at the bend in said fresh air passage.

In witness whereof, I hereunto subscribe my name this 8th day of April, 1922.

ROBERT F. BRACKE.
